APPARATUS FOR APPLYING A BEAD TO
GLASS TUMBLERSPerry A. Becker, Toledo, Ohio, assignor to Owens-Illinois
Glass Company, a corporation of Ohio

Application January 4, 1955, Serial No. 479,720

12 Claims. (Cl. 118—218)

My invention relates to apparatus for use in applying a coloring or decorating material to the rim surfaces of the glass tumblers or other articles. As herein shown and described, the invention is designed for applying a surface coating of gold or other colored ink or material to the beaded rims of glass tumblers.

The invention provides a plurality of units each including a decorating roll of rubber or similar material by which the ink or decorating material is applied to the rim surfaces of the workpieces. The article to be decorated is mounted for free rotation about its axis and is held in rolling contact with the decorating rolls. The latter are symmetrically arranged with respect to the workpiece and its support in a manner to apply a balanced pressure which prevents tilting or misplacement of the article. The coloring or decorating material is continuously applied to the decorating rolls by cylindrical transfer rolls.

Referring to the accompanying drawings:

Fig. 1 is an elevational view of a preferred form of the decorating apparatus, with parts broken away and parts in section;

Fig. 2 is a plan view of the apparatus;

Fig. 3 is a view as indicated by the line 3—3 on Fig. 2, with parts in section and parts broken away; and

Fig. 4 is a diagrammatic plan view showing an arrangement of the decorating rolls and the workpiece.

Referring particularly to Figs. 1 and 2, the apparatus comprises a plurality of frusto-conical rolls 10 by which the ink or decorating material is applied to the beaded rim 11 of the article 12, herein shown as a glass tumbler. A frame or bracket 13, mounted on posts 14, provides a support of the apparatus. A plurality of stationary decorating units 15 which may be of like construction are symmetrically arranged around the vertical axis about which the workpiece 12 is rotated during the decorating operation.

Each of the units 15 comprises a frame member or arm 16 extending radially outward from a hub 17. Mounted on the arm 16 is a carrier 18 for the roll 10. The carrier 18 is adjustable horizontally along the arm 16 for adjusting the roll 10 for articles of different diameters. The carrier 18 comprises vertical arms 20 extending downward below the arm 16 and at the lower end of which a short arm 21 is connected by a pivot rod 22. The roll 10 is mounted for free rotation on a pin 21a on the arm 21. A coil spring 23 under compression counterbalances the weight of the roll 10 and causes the roll to bear lightly on a transfer roll 24. The roll 24 is rotated as presently described about a horizontal axis.

The ink or decorating material, which may be in liquid or semi-liquid form, is fed downward by gravity through a tube 26, the lower end of which is directly over and in close proximity to a small cup 27 which forms a reservoir. The cup 27 bears against the cylindrical surface of the inking roll 24 by which the ink is transferred to the decorating roll 10. The cup 27 extends along that portion of the roll 24 which is directly over and in

contact with the roll 10. The cup or reservoir 27, which may be of sufficiently soft and resilient material to maintain close contact with the transfer roll 24, is yieldingly held against the roll by a leaf spring 30 attached to the carrier 18, the tension of the spring being adjustable by a thumb screw 31. The carrier 18 which is adjustable along the arm 116 is clamped in adjusted position by a clamping screw 33.

The rolls 24 are rotated continuously by an electric motor 35 mounted on the frame 13. The driving connections from the motor to the rolls 24 include the motor shaft 36, bevel gears 37, a vertical shaft 38, coupling 39, shaft 40, and a bevel gear 41. The gear 41 runs in mesh with gears 42 on the shafts 43 of the rolls 24. With these connections the decorating rolls 10 are rotated continuously about their axes.

The workpiece or tumbler 12 is supported on a pad 45 on the upper end of a stem 46 journaled for free rotation in a carrier 47. The axis of the stem 46 is in vertical alignment with the drive shaft 40. The carrier 47 with the workpiece or tumbler 12 thereon, is moved vertically upward to bring the workpiece into engagement with the rolls 10 for the decorating operation. The upward pressure of the tumbler is sufficient to indent the soft rolls 10 of rubber or like material sufficiently to cause the contacting surface of the roll to embrace a substantial portion of the bead 11. The width of the color band or decoration thus applied is determined by this pressure, the consistency of the roll and the contour of the bead or surface of the workpiece.

As shown in Fig. 4, the decorating rolls 10 are symmetrically arranged with respect to the workpiece 12 and its vertical axis of rotation. The frusto-conical rolls are arranged with their axes in vertical planes radial to the said axis of the workpiece. The axes of the rolls are also downwardly and outwardly inclined with respect to such vertical axis. The surfaces of the rolls at their points of contact with the workpiece are also downwardly and outwardly inclined at a somewhat greater angle to the horizontal than their axes (Fig. 1).

At least three rolls 18 are used for the decorating operation, the rolls being equally spaced circumferentially of the workpiece. It will be apparent that with this arrangement of parts the workpiece 12 when brought into contact with the decorating rolls 10 is positively held against any lateral or tilting movement. At the same time the workpiece is free to be rotated about its vertical axis by the decorating rolls 10 which are continuously rotated about their axes by the motor 35. The workpiece 12 when moved upwardly into contact with the rolls is immediately rotated about its axis by the frictional driving contact of the rotating rolls 10 with the rim surface or bead 11. This rotation is preferably continued through somewhat more than one complete revolution of the workpiece so that each of the decorating rolls traverses the complete circumference of the rim or bead 11. The number of decorating rolls may be increased if desired.

Modifications may be resorted to within the spirit and scope of my invention.

I claim:

1. Apparatus for applying decorating material to the surface of a workpiece, comprising means for mounting the workpiece for free rotation about an axis, decorating rolls symmetrically arranged with respect to said axis and positioned to bear against the surface of the workpiece, means for supplying a decorating material to the surfaces of said rolls, and means for rotating the rolls while in contact with the workpiece and thereby rotating the workpiece and applying the decorating material to said surface of the workpiece, the means for rotating the decorating rolls comprising a drive shaft in line with and

rotatable about said axis, a stationary supporting frame in which said shaft is journaled for rotation, a driving pinion keyed to said shaft, and power transmitting devices individual to said decorating rolls each comprising a gear driven by said pinion, and means for transmitting motion from the gear to the decorating roll.

2. The apparatus defined in claim 1, the last mentioned means comprising an inking roll driven by said gear and running in contact with the decorating roll and applying a decorating material thereto, and means for applying the decorating material to the inking roll.

3. The apparatus defined in claim 2, the means for supplying the decorating material to the inking roll comprising an ink well in the form of an open-sided container with the open side bearing against the inking roll, springs means for holding the ink well against the inking roll, and means for supplying ink to said well.

4. Apparatus for applying decorating fluid to a circular, circumferential surface of a workpiece comprising means for mounting the workpiece for rotation about the axis of said surface, decorating rolls positioned to engage said surface, a stationary frame, rock arms pivoted to said frame and in which the rolls are mounted for free rotation about their axes, means by which said rock arms are held and maintained in a substantially constant relative position, means for applying a decorating fluid to the surfaces of said rolls, and means for rotating the rolls about their axes while in contact with the workpiece and thereby rotating the workpiece about its axis and causing the rolls to apply a coating of the said decorating fluid to the said surface of the workpiece.

5. Apparatus for applying decorating material to a circumferential surface of a workpiece, means for supporting the workpiece for free rotation about the axis of said surface, decorating rolls mounted for rotation about their axes, the axes of the rolls being disposed radially with respect to the said axis of the workpiece and also inclined to the said axis, a frame carrying the rolls, means by which their axes are maintained in substantially constant relative position, means for rotating the rolls, means for applying a decorating fluid to the surfaces of the rolls, and means for maintaining a pressure of the rolls against the said circumferential surface.

6. Apparatus for decorating the circular rim surface of a tumbler or other article, said apparatus comprising a pad for supporting the article for free rotation about the axis of said rim surface, at least three frusto-conical decorating rolls symmetrically arranged with respect to the axis of rotation of the article and equally spaced circumferentially of said axis, the rolls having their axes inclined to the axis of the said surface and positioned with the peripheral surfaces of the rolls in contact with the said rim surface of the article, means for applying a decorating material to the surfaces of the rolls, and means for rotating the rolls and thereby rotating the article and applying the decorating material to said rim surface, the said pad being free for rotation by and with the said article during the rotation of the article.

7. Apparatus for decorating the rim surface of a tumbler or other workpiece, said apparatus including a pad forming a holder for the workpiece, a carrier in which said holder is mounted for free rotation about the vertical axis of the workpiece, a plurality of decorating rolls mounted for rotation about axes radial to said vertical axis with said rolls bearing on said rim surface, means for applying a decorating ink to the surfaces of the rolls, means for rotating the rolls about their axes, said carrier serving as a means for holding the workpiece against the

rotating rolls and thereby causing the workpiece to be rotated about its axis by said rolls and the decorating material applied to the said rim surface, the means for rotating the decorating rolls comprising a drive shaft rotatable about the said vertical axis, the means for applying the decorating ink to the rolls comprising inking rolls individual to the decorating rolls, said inking rolls running on and driving the decorating rolls, and means forming driving connections between said drive shaft and inking rolls.

8. The apparatus defined in claim 7, the surfaces of the decorating rolls at their points of contact with the workpiece being downwardly and outwardly inclined with respect to said vertical axis, whereby upward pressure of the workpiece against the decorating rolls causes a reacting pressure of the decorating rolls downwardly and inwardly against the said rim surface, thereby securely holding the article against tilting or lateral movement while the decorating material is applied to said rim surface.

9. Decorating apparatus comprising at least three decorating units, each unit including a cylindrical inking roll, means for mounting said rolls with their axes horizontal, each said unit comprising a decorating roll positioned beneath the inking roll and having a frusto-conical surface in line contact with the cylindrical surface of the inking roll, means for yieldingly holding said surfaces in contact, a motor, and means forming driving connections between the motor and the inking rolls for continuously rotating the inking rolls and imparting continuous rotation to the decorating rolls, means including a pad for mounting a tumbler or other workpiece for free rotation about a vertical axis with the workpiece below the decorating rolls, and a carrier for the pad for holding the workpiece against the decorating rolls and thereby causing the workpiece to be rotated by said rolls, ink wells individual to the inking rolls, each said ink well being in the form of an open-sided container with the open side bearing against the inking roll, spring means for holding the ink wells against the inking rolls, and means for supplying ink to said wells.

10. The apparatus defined in claim 9, the axes of the inking rolls being arranged radially with respect to the axis of rotation of the workpiece.

11. The apparatus defined in claim 10, including a support on which said units are mounted and adjustable radially toward the said axis of rotation.

12. Decorating apparatus comprising a plurality of decorating units, each unit including a horizontal inking roll, a supporting frame in which the inking rolls are mounted for rotation about horizontal axes, said axes being radial to and symmetrically arranged about a vertical axis, the said units including frusto-conical decorating rolls individual to the units and running in contact with the respective inking rolls, means for applying ink to the inking rolls, a motor, means providing driving connections from the motor to the inking rolls for simultaneously rotating the inking rolls and causing them to rotate the decorating rolls, said driving connections including a vertical shaft concentric with said vertical axis, and gears connecting said shaft with the inking rolls.
